US0D1094459S

(12) **United States Design Patent** (10) **Patent No.:** **US D1,094,459 S**
(45) **Date of Patent:** **** Sep. 23, 2025**

(54) **INTAKE MANIFOLD**

(71) Applicant: **DEEPMOTOR INC**, Fontana, CA (US)

(72) Inventor: **Yong Wei**, Fontana, CA (US)

(73) Assignee: **DEEPMOTOR INC**, Fontana, CA (US)

(**) Term: **15 Years**

(21) Appl. No.: **29/974,369**

(22) Filed: **Nov. 21, 2024**

(51) **LOC (15) Cl.** **15-01**

(52) **U.S. Cl.**

USPC **D15/5**

(58) **Field of Classification Search**

(57) **CLAIM**

The ornamental design for an intake manifold as shown and described.

DESCRIPTION

FIG. 1 is a front, right, top perspective view of an intake manifold;

FIG. 2 is a rear, bottom perspective view thereof;

FIG. 3 is a right side thereof;

FIG. 4 is a left side thereof;

FIG. 5 is a front view thereof;

FIG. 6 is a back view thereof;

FIG. 7 is a top plan view thereof; and,

FIG. 8 is a bottom plan view thereof.

The broken lines show features of the intake manifold that form no part of the claimed design.

1 Claim, 8 Drawing Sheets
